(57) **CLAIM**

The ornamental design for a wireless receiver for car, as shown and described.

DESCRIPTION

FIG. 1 is a front elevational view of a wireless receiver for car showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof shown; and,

FIG. 8 is a second perspective view thereof shown.

The broken lines shown in the drawings depict portions of the wireless receiver for car that form no part of the claimed design.
